Primary Examiner—M. N. Pandozzi

(57) **CLAIM**

The ornamental design for a lemon tea infuser, as shown and described.

DESCRIPTION

FIG. 1—is a front elevational view of a lemon tea infuser showing my new invention.

FIG. 2—is a left side elevational view thereof, the right side being a mirror image.

FIG. 3 is a top plan view thereof;

FIG. 4 is a rear elevational view thereof; and,

FIG. 5—is a bottom plan view thereof.
